UNITED STATES PATENT OFFICE.

HORACE A. ROBISON, OF CLEVELAND, OHIO.

IMPROVEMENT IN APPARATUS FOR PRESSING AND IRONING HATS.

Specification forming part of Letters Patent No. 35,954, dated July 22, 1862.

To all whom it may concern:

Be it known that I, HORACE A. ROBISON, of Cleveland, in the county of Cuyahoga and State of Ohio, have invented a new and useful Machine for Ironing or Pressing Hats; and I do hereby declare that the following is a full and exact description thereof, reference being had to the accompanying drawings, and to the letters of reference marked thereon, making part of this specification, in which—

Figure 1 is a sectional side elevation through the center. Fig. 2 is a sectional front elevation through the center. Fig. 3 is a sectional side elevation through the center, with the collar which supports the hat-block inclined. Fig. 4 is a sectional front elevation through the center, with the collar which supports the hat-block inclined, thereby bringing the back part of the collar in perspective. Fig. 5 is a top view of the disk, which will be explained hereinafter.

A in Fig. 1 is the vertical front of a tapering mortise.

A² in Fig. 1 is the inclined back of the mortise with its top inclined toward the vertical front A, which produces a tapering mortise with its base wider than the top.

B is a tapering or wedge-like tenon, with a vertical front and inclined back reversed to the inclined back A² of the mortise. The bottom of tenon B is V-shaped.

C is a lateral projection in the bottom of the mortise, with the front inclined to correspond with the back part of the V-shaped bottom of tenon B, which causes the tenon B to be pressed against the front A of the mortise, thereby holding the collar firmly in a horizontal position.

D in Fig. 1 is a disk with V-shaped notches, (shown by the dotted lines; also shown in Fig. 5,) from which the tenon B projects at right angle on the bottom side. D² is a round tenon or journal projecting from the top side of the disk D. The tenon B, disk D, and journal D² are all of one piece, or cast together.

E F G form the collar upon which the various kinds of hat-blocks are placed for ironing and pressing the hats.

E is a ring screwed to the under side of the wooden part of the collar F, with V-shaped teeth projecting from the under side, which fit into the V-shaped notches in the disk D.

F is a round or oval-shaped board upon which the blocks are placed.

H is a thin band fastened around F to prevent the blocks from getting off.

G is a sleeve or thimble screwed to the top of F.

E, F, and G are so constructed as to slip over and turn with ease around the round tenon or journal D². When the collar is turned in either direction, the V-shaped teeth slip out of the V-shaped notches and fall into the next in position. The hat-blocks are thus held in any horizontal position.

B in Fig. 3 shows the tenon inclined so as to bring the inclined back of tenon B in contact and parallel with the inclined back A² of the mortise. Tenon B is held in an inclined position by bringing the front part of the V-shaped bottom of tenon in contact with the back of the projection C in the bottom of the mortise, thereby holding the collar firmly in an inclined position. The inclination can be changed by drawing the tenon B out of the mortise and turning it half-way round and replacing it again.

If desired, the collar may be permanently fastened to the hat-block.

It will be seen by this arrangement that the block with the hat can be turned or placed in any position desired with ease and expedition.

After thus describing the construction and operation of my machine, what I desire to secure by Letters Patent is—

1. The tapering tenon B and tapering mortise with the projection C, for the purpose set forth.

2. The collar and tenon or journal D², in combination with the tapering tenon B and mortise, as above described.

H. A. ROBISON.
